UNITED STATES PATENT OFFICE

PAUL J. TIMBERLAKE, OF JACKSON, MICHIGAN

DRYING FORM

Application filed January 29, 1929. Serial No. 335,842.

The present invention relates to hinged frames employed to support and stretch garments, such as socks, infants' shirts, etc., while drying; and has for its object to improve the construction of the same, as will be pointed out, particularly by producing frames that have no exposed parts of metal. In making such drying frames it has heretofore been the practice to connect together the several relatively movable parts by metallic hinges, usually in the form of metal ferrules. These, and other metal parts of the frame, having repeatedly brought into contact with them the wet garments to be stretched and dried, almost inevitably sooner or later begin to rust or corrode, and then garments applied thereto are stained. In the practice of the present invention the metal frames employed to support the garments or other articles to be dried are covered with rubber tubing or some other suitable water proof sheathing and the movable parts of each frame are united by hinges formed of flexible tubular waterproof sheaths, such as rubber tubing. By the use of this invention, not only are all metal parts covered so that the garments applied to the frames do not come into contact with any metal, but also the metal of the frame is very effectively protected against moisture and the tendency thereof to rust or corrode is reduced to a minimum.

In the accompanying drawings, wherein the invention is illustrated,

Fig. 1 is a perspective view of a frame for supporting a pair of stockings while being stretched and dried, embodying the present invention, parts being broken away.

Fig. 2 is a view of a piece of stock material from which the frame is produced.

Figs. 3 and 4 are views illustrating steps in the manufacture of a frame such as shown in Fig. 1 from stock material such as presented in Fig. 2.

Fig. 5 is a view of a hinged stretching and drying frame for a shirt, embodying the present invention.

Fig. 6 is a view illustrating steps in the manufacture of an article such as shown in Fig. 5.

50 The material from which frames embody-

ing the present invention are constructed is represented in Fig. 2 and consists of wire 2 covered with a rubber sheathing 3. The method of producing such material constitutes no part of the present invention.

In making a frame for stretching and drying stockings, such as represented in Fig. 1, a pair of duplicate forms are produced and these are hinged together near their upper ends permitting the article to be hung upon a support after the stockings are applied thereto, during the drying process. The stock material, of the character for instance illustrated in Fig. 2, is shaped by any approved means into desired form with the ends of the material turned toward each other to form a cross bar 4 at the top of the form, that is at the end opposite the foot portion. These ends of the form are finally caused to abut and are united by welding or brazing. Before the ends of the wires 2 are thus united a pair of forms are brought together as indicated in Fig. 3 and a piece of rubber tubing 6 is slipped over an inturned end of each form, uniting them as an elastic ferrule. This piece of rubber is then forced back over the frames past the bends 7 until it occupies a position surrounding the long side pieces 8 of the forms, as represented in Fig. 4 and in dotted lines, Fig. 3. The rubber sheathings 3 at the ends of the inturned pieces 4 of the forms are then crowded back as represented in Fig. 4, leaving exposed the ends of the wires 2 which are brought together and united by brazing or otherwise. After the wires have been united 85 sheathings 3 covering them are slipped back to place until their ends abut. The piece of tubing 6 is then slipped back into place as represented in Fig. 1, when the article is completed.

It will be seen that by this construction the only places where the metal parts 2 of the frame are not completely covered is where the ends of the sheathing 3 abut at about the middle of the end cross bars 4 of the frame, and that the exposure at these points is negligible, as the ends of the sheathing closely abut, and may, if desired, be united by rubber cement, or other waterproof material; and these abutting ends of the sheathing 3 are within the

tubular rubber sheath 6, which constitutes the hinge of the frame. If any moisture should reach the metal and the latter rust or corrode it will not stain the articles that may be applied to the frame for stretching and drying, as the only parts of the metal that are liable to corrosion are within the sheathing 6, constituting the hinge.

The hinge 6 is elastic and waterproof so that all liability of parts binding or becoming stuck in use is removed; it is very durable, and may be manipulated as described in the manufacture of the frame, so that its integrality as a tube is maintained from the first to the last.

In Fig. 5 is represented the invention as applied to a frame for drying shirts, in which 15 indicates the body form and 9, 9 the arm forms, hinged to the body form by tubular rubber hinges 6 such as have already been described. In constructing the frame shown in Fig. 5 the body form thereof, 15, is shaped from a single piece of wire the ends of which are preferably brought together and united at the lower cross member 10 of the form. The ends of the wires that constitute the arm forms are brought together and united at points 11, and are covered by the tubular hinge parts 6 when the frame is assembled.

The side members 12 of the body form 15 of the frame are bent at points 13 to prevent the hinges 6 from slipping from their desired positions such as indicated in the drawing.

In assembling the parts of the frame shown in Fig. 5 the two tubular pieces of rubber tubing that are to serve as the hinges are slipped on to the body frame and along the respective sides 12 thereof to positions above the bends 13. The ends of the wire constituting the frame may then be united completing the cross bar 10. One of the arm forms, its ends still ununited, is then placed into the position represented in Fig. 6, that is lying across the upper end of the form 8, and one free end of the wire constituting the form 9 is inserted into the tubular hinge piece 6. This piece is then worked around the bends 14 of the frame pieces to the position indicated in dotted lines in Fig. 6. The ends of the wire constituting the sleeve form 9 may now be united, the sheathing 3 thereof being pushed back to expose the joint while the union is being made. This having been completed the ends of the sheathing 3 are brought together and the tubular hinge piece 6 is slipped back in place, as represented in Fig. 5.

The steps just described are then repeated in the attachment of the second sleeve form 9.

It will be understood from the foregoing description taken in connection with the drawings that the invention may be embodied in articles of different constructions and forms; and further that it is to be under-

stood that various modifications and changes in the parts of the invention come within the purview of the present invention. For instance the sheathing employed to protect the metal of the frames might be in the form of a water proof enamel applied to the wire in lieu of the loosely applied rubber water proof sheathing which is shown in the drawings. The invention therefore is not limited to the specific showing thereof herein presented, nor beyond what is expressed in the claims.

Claims:

1. A metal frame formed of a plurality of parts hinged together, the hinges being flexible, integral and tubular, and surrounding portions of each of the parts they unite.

2. A frame comprising a plurality of parts formed of wire shaped to the desired form and hinges uniting the parts of the frame, the hinges being of flexible, unbroken, tubular material.

3. A frame consisting of a plurality of parts formed of wire shaped to the desired form, the wire being sheathed with water proof material and hinges uniting the parts of the frame the hinges being of flexible, integral, tubular, waterproof material.

4. A drying frame consisting of a plurality of parts formed of wire covered with a rubber sheathing and hinges uniting the parts of the frame consisting of sections of integral, flexible, rubber tubing.

5. The herein described method of producing a hinged frame from wire, covered with a rubber sheathing, which consists in bending the sheathed wire into the desired forms, the ends of the wire being brought close together but remaining unconnected, assembling a pair of forms with portions thereof of side by side, passing over such portions a section of integral flexible tubing, and forcing the same along the side-by-side portions of the two forms until the ends of the form extend beyond the tubular section, then uniting the separated ends of the form and finally forcing over the said united portions of the form the said tubular piece to serve as a hinge uniting the parts of the frame.

In testimony whereof I affix my signature.

PAUL J. TIMBERLAKE.
